GENERATOR GASOLINE BURNER

Isaac Vernon Brumbaugh, St. Louis, Mo., assignor
to American Stove Company, St. Louis, Mo., a
corporation of New Jersey

Application June 26, 1930, Serial No. 463,931

15 Claims. (Cl. 158—61)

This invention relates to improvements in generator gasoline burners and the principal objects of the invention will first be briefly referred to. It is well known that all grades of gasoline are composed of light and heavy constituents, and that in generating any grade into vapor, the lighter or more volatile constituents are the first to be vaporized. I find that it is from the heaviest constituents that carbon is formed and accumulates and interferes with the operation of the generator mechanism. Therefore one of the objects of my present improvement is to hold the heaviest constituents in the generator and prevent them from contacting with said mechanism in the vaporization thereof and thereby substantially avoid the well known interference of carbon with the operation of the burner.

Another object of the present invention is to so construct the generator and its mechanism, that said mechanism is not subjected to the direct heat of the flame that heats the generator, whereby the accumulation of carbon to interfere with its working is avoided.

It is also well known to those skilled in the art, that either an auxiliary burner or torch is used for initially heating the generator, and it is a further object of the present invention to avoid said auxiliary means and at once produce an initial heating blue flame having substantially greater heating effect in the generator, thereby heating it in less time and without disagreeable odor and smoking.

Further objects of the present improvement have not been thus far described or referred to but they will be readily understood from the following description.

In the accompanying drawings:

Figure 1 is a top plan view of a gasoline stove or range that embodies my improvements.

Fig. 2 is a diagrammatical view showing the several elements which comprise my new burner.

Fig. 3 is a top plan view of one of the top burners of my improved range and the mixing pipe shown in horizontal sectional view.

Fig. 4 is a side elevation of Figure 3 looking at it from the front.

Fig. 5 is a side elevation of Figure 3.

Fig. 6 is a sectional view on the line 6—6 looking in the direction indicated by arrow.

Fig. 7 is a vertical sectional view on the line 7—7 of Figure 3.

Fig. 8 is an enlarged longitudinal sectional view of the controlling valve for the air and vapor that are fed to the mixing tube of the burner.

Fig. 9 is a top plan view of the combined top burner and oven burner.

Fig. 10 is a side elevation of the top burner which also supplies vapor for the oven burner.

Fig. 11 is a side elevation of the burner 10 with the generator tube and the surrounding housing therefor removed.

Fig. 12 is a horizontal sectional view through the top burner that also supplies vapor to the oven burner.

Fig. 13 is a horizontal sectional view through the top burner, the generator tube and surrounding housing removed.

Fig. 14 is a detached perspective view of the generator tube and its supporting housing.

Fig. 15 is a detached perspective view of the housing 43.

Referring to the drawings in which 1 indicates a burner having connected therewith a suitable mixing tube 2. This mixing tube communicates with the interior of the burner 1 through suitable opening 3. This mixing tube is located as here shown at the rear side of the burner and it curves around to the left side of the said burner and is provided with a head-like portion 4. This head-like portion is provided with a suitable air inlet 5, and passing into this head-like structure is the gasoline nozzle 6. A suitable gasoline tank 7 is located at one side of the stove frame 8 which is shown in Figure 1 in dotted lines. This gasoline tank is supplied with gasoline through a suitable cap opening 9 and air is forced into this tank by means of a suitable pump 10 that is connected with the said tank by a pipe 11. The mixing tube 2 therefore constitutes what may be aptly termed as a manifold through which the mixed fuel and air flows to the several burners.

The air fed through this pipe 11 to the tank is controlled by a suitable valve 12 placed in the upper end of a tubular section 13. When the tank is to be supplied with air this valve 12 is turned upward until its valve is unseated when air will pass into the said tank. Also passing into the tank 7 is a tubular member 14 that has its lower end 15 adjacent the bottom of said tank. A pipe 16 is connected with this tubular portion 14 outside of the said tank and a suitable valve 17 controls the flow of gasoline to the said pipe 16. It will be understood that the gasoline being under air pressure it will be forced through the lower end 15 of the tubular member 14 and into the pipe 16. This pipe 16 communicates with the generating tube 18 and this generator in turn communicates with the gasoline nozzle 6 that feeds for initial starting the atomized gaso-

line and air through an opening 19 into the mixing chamber 2. An air pipe 20 has its outlet end 21 communicating with the restricted portion 22 of the nozzle 6 and its inlet end 23 communicating with the tubular portion 13 at a point below the valve 12. Located intermediate the ends of this pipe 20 is a suitable valve housing 24 and the valve 25 located in this housing controls the air from the tank through this pipe 20 to the outlet end 21 thereof and thereby controls the air passing through the restricted portion together with atomized gasoline mist that flows through the nozzle 19 when the burner is being started.

A valve 26 is adapted to cut off the flow of gasoline through the nozzle when it is on its seat 27. The stem 28 that carries this valve is provided with a screw-threaded part 29 that engages with a screw-threaded part 30 on the tubular portion 31 that is connected with the nozzle 19. The outer end of this stem 28 is provided with a handle 32 whereby the valve may be moved backward and forward within the tubular portion 31. Attention is called to the extension 33 of the valve 26 that passes through the restricted portion 22, and projecting from this stem 33 is a needle valve 34 that operates in connection with the nozzle opening 19. This nozzle portion 19 is preferably made separate from the tubular member 31 and is screwed in its extremity as shown at 35.

The burner 1 is provided at its under side with a depending portion 36 that has longitudinal slots 37, and this depending portion forms a sub-fire for heating the generator 18 that is detachably supported under the burner 1 and extends at an angle parallel with the sub-burner 36. This sub-burner communicates with the mixing tube 2 so that the said sub-fire burner 36 is supplied from the mixing tube through the openings 3 and 39 as shown in Figure 6. It therefore will be understood that the fuel for the sub-fire first passes to the said manifold or mixing tube 2 and through the openings 3 and 39 (Fig. 6) to the said sub-fire burner 37.

As shown the generator 18 (Fig. 7) is inclined upwardly from its inlet end 40 to its outlet end 41 (Fig. 8) which is in communication through the opening 42 with the tubular portion 31 that carries the gasoline nozzle 6. For the purpose of supporting this generator and holding it in this inclined position a suitable housing 43 is provided through which the generator 18 passes as shown in Figure 7. The vertical ends of this housing 43 are detachably connected by cotter pins 44 that pass through the ears 45 of the housing and the burner. This inclination is very important and its operation will be referred to further on in this description. This housing 43 serves as means for confining the heat from the sub-fire flame around the said generator by means of its vertical wall 43' and at the same time serves as stated as means to insure that this generator is supported at the proper inclination in respect to the said burner. Attention is also directed to the fact that the sub-fire member 36 extends in the same direction as the generator and that the bottom 46 of this housing 43 is similarly inclined as shown in Figure 7. This housing 43 has its end walls provided with open ended vertical slots 43^a which receive the tube 18 of the generator. Outwardly extending perforated ears 43^c are located at the upper ends of the said end walls and these ears are provided with perforations through which the cotter pin 44 passes as shown in Figure 5. These ears 43^c are in separated rela-

tion so that they rest at the inner side of the ears 45 of the burner. A side wall 43^b also forms a part of the said housing 43.

Attention is called to the construction of the end 4 of the mixing chamber 2. This end of the mixing chamber communicates with the burner 1 as before stated and its lower wall 48 declines gradually to a pocket 49. This pocket 49 has one end of a pipe 50 communicating with the said pocket and the opposite end of the pipe is connected with a suitable reservoir 51 that for convenience is shown located at the rear side of the stove. The object and function of this pocket and the pipe 52 that connects it with the reservoir 51 and this reservoir will be explained presently.

The pocket 49 is to receive the condensed gasoline produced from the mixture of gasoline mist and air and which is conveyed through the pipe 52 to the tank 51. A vertically arranged chamber 53 is connected by a pipe 54 with the bottom of the tank 51. A float 55 is located in the chamber 53 which has a stem 56 connected with it and projecting through the top of the chamber 53. This chamber 53 is located in a convenient place for the operator to observe when the tank 51 is full of the condensed gasoline. When this point is reached in the operation of the burner the operator by removing the drain plug 57 located in the bottom of the chamber 53 can empty the gasoline from the tank 51.

The pipe 52 connected with the upper portion of the tank 51 is provided with a trap 58 located therein at suitable point between the said tank and the pockets 49. The object of this trap is to provide a seal for the gasoline vapor flowing from the nozzle 6 so that there will be no escape of this gasoline vapor to the tank 51 when the burner is in full operation. It will be understood that after the generator and burner are heated up there will be no condensed gasoline flowing to the pockets 49 and hence no condensed gasoline flowing to the drain tank 51. In the event of but one generator being in operation it is necessary that each of the connections 52 be provided with a trap 58 and 58' located between the generators and the reservoir 51 to which the said pipes are connected. Otherwise there would be an escape of vapor from the generator in operation to the burner not in operation. The arrangement here prevents that result.

For the purpose of indicating the air pressure in the gasoline supply tank 7 a suitable air pressure indicator 59 is attached to the tank. It will be understood that the tank must be supplied with a certain amount of air pressure to force the gasoline from the tank 7 to the nozzle 6 and this indicator will show to the operator when there is the proper amount of pressure in the tank for that purpose.

By reference to Figure 1 it will be observed that the top burner portion comprises the said burner 1, a similar burner 1' and two burners 1² and 1³ and also an oven burner 1⁴. The gasoline generated by the burner 1 supplies vapor for the burners 1² and 1³ while the burner 1' supplies gasoline vapor for the oven burner 1⁴. The burners 1² and 1³ are provided with supply tubes 60 and 61 and these two supply tubes are joined by a cross supply tube 62, which in turn is connected with the mixing tube 2 of the burner 1 by a tube 63, while the oven burner 1⁴ has a supply tube 64 that communicates with the mixing tube 4' of the burner 1⁴.

I will first explain the operation of the burner 75

1 and then will explain the operation of the other burners.

Initial starting of burner 1

5 The operator first closes the gasoline valve 17 and then opens the air valve 12 and by means of the pump 10 the tank is supplied with the proper air pressure for operation, about twenty pounds. The generator valve 26 being closed through the medium of its handle 32 the gasoline flows from the tank 7 to the pipe 16 and through the pipe to the generator 18. The parts of the stove all being in the positions indicated then to start operation of the burner 1 the operator opens the air valve 24 which feeds air through the pipe 20' to the outlet 21 and to the nozzle 6. Then while this air valve is open the operator opens the valve 26 and gasoline is forced through the restricted portion 22 to the nozzle 6, the air and gasoline being mixed to some extent before it reaches the nozzle 6 produces a liquid mist. This mixture of gasoline mist and air flows into the mixing chamber 4 where additional air is drawn into the head 4 of the mixing tube through the opening 5. At this time the burner and generator of course are not heated. The operator through the medium of the handles which control the air valve 24 and the gasoline valve 26 can immediately cause a cold mixture (which will burn with a blue flame) which will pass through the mixing tube to the burner 1 and this cold mixture is lighted and at the same time this cold mixture which supplies a blue flame is fed to the sub-fire burner 36 and this cold mixture flows through the slots 37 of the sub-fire burner. In fact this cold mixture is supplied simultaneously to the burner 1 and the sub-fire 36. Hence when the burner 1 is lighted from above, this cold mixture from the sub-fire instantly lights at the same time through the opening 65. Therefore the burner 1 and the sub-fire burner 36 are both producing a blue flame from this cold mixture. It is well known that this blue flame is much hotter than if it were yellow so that in about forty seconds time the burner, the generator and their parts are sufficiently heated to produce the gasoline vapor to the sub-fire and also the burner 1 and at this time the air valve 24 will be closed and the burner will continue to operate normally producing the usual blue flame at the burner 1. During the operation of the burner 1 the sub-fire burner continues to burn and the generator 18 is kept hot by this sub-fire flame.

55 In the initial starting of the burner and before the burner, generator and their parts become heated up from the flame, the mixture of air and gasoline causes a mist to flow through the opening 19 (Fig. 8) into the mixing chamber 4 in which additional air flows through the opening 5 to this misty mixture. All parts of the burner and the generator and the mixing tube being cold at this time there is some condensation of this misty mixture. In order to take care of the condensation of the gasoline caused by striking the cold parts with which it comes in contact I provide the mixing tube 2 with a pocket 49 that depends from the lower wall and the lower wall 48 of this mixing tube is inclined toward the said pocket so that any condensed gasoline finds its way to this pocket and is drained through the pipe 52 to the drain tank 51. It will be understood of course that when the parts of the burner and generator are sufficiently heated then condensation of the gasoline ceases. This pipe 52

is provided with a trap 58 that serves the purpose before mentioned of preventing the flow of gasoline vapor from the mixing tube 2 to the tank 51.

Purpose, function and operation of the inclined generator

5

In Figure 7 the generator 18 is shown in an inclined position to which brief mention has heretofore been made. The reason for this arrangement of the generator 18 will be stated as follows. When the burner is started the generator is of course full of gasoline throughout its length and this causes a visible spray made up of a mixture of gasoline and air to flow through the nozzle opening 19. When the burner becomes heated and is normally operating then the gasoline in the generator forms a level substantially at *a* in Figure 7. That is to say, the gasoline is under pressure in the tank, say twenty pounds, and substantially twenty pounds of pressure is produced in the part *b* of the generator so that the pressure at *b* is substantially equal to the pressure in the tank 7 and the gasoline then reaches its level in the generator which is found to be substantially the point *a* of Figure 7. Hence the raw gasoline (after the main burner 1 is heated) never reaches the gasoline valve 26, its reduced portion 33, its needle 34 and its nozzle opening 19 when the generator is in full operation. I find that in this arrangement the accumulation of carbon in the generator and in the gas valve tube 31 and around the screw threads 29 and the nozzle and parts cooperating with the nozzle is exceedingly small and that the burner can be operated substantially without any obstruction occurring in these parts. 35

I believe this to be caused by reason of the fact that gasoline is composed of course of lighter and heavier particles. These lighter particles are formed into a gas under the warm air conditions and in fact these lighter particles will evaporate under atmospheric temperature while the heaviest particles of the gasoline require considerable heat in order to vaporize it. The lighter particles fill the portion *b* of the generator and the lighter portions which are formed into gas and which reach the valve 26 and the screw thread 29 and the nozzle and its parts substantially do not form into carbon. In fact a "cracking" or complete vaporization of the gasoline is necessary to form any appreciable forming of carbon. Hence the above mentioned parts are substantially free from carbon accumulation.

I also believe from experiments made by me that substantially all of the heavy part of the gasoline which causes carbon to form is held for a time in solution by the raw gasoline in the generator tube 18. These heavy particles being continuously mixed with the lighter raw gasoline particles, the heavy particles, as stated, are held substantially in solution. These are some of the reasons which I believe enable my improved burner to operate for such long periods of time without any clogging of the generator. By placing this generator on an incline as shown I am able to hold some raw gasoline in the generator while its upper end is free from this raw gasoline when the generator, the burner, and their parts become sufficiently hot to cause the generated vapor to be supplied to the mixing tube 2.

In fact the following is clearly visible in the operation of my burner, viz: When the burner is being started a mist of gasoline can be clearly seen as issuing from the nozzle 6 when the generator, burner and its parts are cold, but when these parts become sufficiently heated for the 75

normal operation then the gasoline vapor issuing through the nozzle opening 19 is clearly invisible.

I have not operated this burner sufficiently long up to the present time to determine positively whether an unobstructed generator tube placed at an inclination as here shown will operate substantially indefinitely without becoming clogged up with carbon but I have satisfied myself that it can be operated for a sufficiently long period of time to enable it to work under the ordinary periods of time that the stove is in operation for a period of several years without becoming clogged up.

A generator tube without any obstructing material in it such as here shown, can be readily cleaned of any obstructing carbon by having its lower end 40 capable of being opened and closed by a screw 66. By removing this screw 66, an instrument can be readily inserted in the generator and substantially clean it of any obstruction therein.

Again I call attention to the fact that in burners heretofore in use the gasoline valve 26, the nozzle 6 and parts thereconnected are subjected to the direct heat from the burner or the sub-fire, when a sub-fire is provided. By this it is meant that usually the tubular portion 31 is the generator which contains the gasoline valve 26 and is directly in the flame of the burner or directly in the flame of the sub-fire. It will be observed that in my improved construction here shown this is not true and that the only heat to which the valve 26, the nozzle etc. are subjected is heat by induction through contact of the generator with the upper end 31 of the valve 26. In this way the parts above mentioned are not subject to the intense heat that they are subjected to in the usual construction of generating burners.

In the usual construction of generating burners the passage inside of the generator tube averages about one thirty-second of an inch and it is only necessary to clog up this small space in order to prevent operation of the burner. Of course this small space can gradually fill up very readily and the efficiency and operation of the burner be materially affected by it. With a generator without any obstruction the above effect can not be present.

The condensed gasoline that is stored in the drain tank 51 is of course not any more dangerous than is the gasoline in the supply tank 7 which has passed the underwriters. The principal object of the tank 51 is to prevent this condensed gasoline from clogging in the burner structure from any cause whatever and thus be more or less dangerous in the hands of a user. If it should be preferred the pipe 52 may be extended to a point removed from the stove. That is to say, the tank 51 could be placed in the cellar, or in fact the pipe 52 in some instances might be extended to the outside of the building and allowed to drain off in the ground. However the construction herein shown is the preferred construction and removes the danger that would be occasioned by the condensed gasoline gathering in the parts of the burner, as for instance one first using the stove and therefore unaccustomed to it, might make several attempts to start it which might cause the condensed gasoline line to be accumulated in the burner. When the stove is finally lighted after several attempts the burning of this accumulated gasoline might startle one unaccustomed to its operation and therefore by some wrong operation might lead

to a fire. It is to prevent any such occurrence that the drain tank 51 is provided. In the operation of the burner this tank is found to be ample for receiving the condensed gasoline. However to prevent the accumulation of this gasoline I provide the communicating chamber 53 so that if by any chance there should be an accumulation of the condensed gasoline it can be drawn from the tank 53 through the drain cock 57.

I have also shown the air passage 20 connected with the gasoline tank 7 as the practical way of supplying air which has several advantages. I will state however that it is not essential to the operation of the burner that the compressed air be taken from the tank containing gasoline, because the operation of the burner would be substantially the same if this air were taken from a tank that does not contain any gasoline and therefore in this case containing no gasoline vapor. It is essential however that the air be compressed so that it will issue under pressure together with the gasoline through the nozzle 6. The supply of air from the gasoline tank 7 as stated has several advantages. For instance if an additional tank for the air be provided which did not contain gasoline and the air fed to the burner exactly as we have herein described, if the pressure in the additional tank were less than the pressure in the gasoline tank the air would not flow—in fact gasoline would flow through the air line into the additional tank. This would mean that the additional air tank would have to be under approximately the same pressure as the gasoline tank in order that the operation herein described be the result. By taking the air from the tank 7 the pressure on the gasoline is always equal to the air pressure and therefore the above unsatisfactory result is not present.

In my improved burner herein described the mixture of air and gasoline in the form of a mist is burned until the sub-fire heats the generator sufficiently to vaporize the gasoline and produce a blue flame independent of the supply of air and at this time the air supply is cut off.

As stated most manufacturers utilize the pipe 31 which contains the valve and its several constructions as a generator. In this instance the stem of the valve is in the region of the sub-fire and there is a clearance between the stem of the valve and the inside wall of the generator tube of about one thirty-second of an inch. Most manufacturers place such generators in a horizontal position and it only requires a few weeks to an extreme of a few months to cause clogging of the generator because of the carbon that is formed and the corrosion that occurs. The threads of the valve of generators of this type corrode and corrosion and carbon pack around the threads and cause the stem to turn quite hard and in fact very frequently cause a twisting of the stem and stop or substantially stop the operation of the burner.

In my construction the generated gas does not pass over the threads of the valve as the valve housing is not in the generator tube and in my construction the additional and separate generator tube is connected near the valve seat. Also in my construction of generator the threads of the valve are not corroded nor does carbon pack in the threads sufficiently to cause hard turning.

It will be observed that the air connection in my construction of generator leads from the gasoline tank 7 and is joined to the valve housing near the orifice 19 and in the construction shown the air

connection is between the said orifice 19 and the valve seat 27. In my construction it is important to have the air connection to the valve near the outlet orifice 19 and that is why the connection is made to the valve housing instead of to the generator. In other words I have found it unsatisfactory to connect the air line from the tank 7 to the gasoline line near the lower end of the generator 18.

10 Attention is also called to the fact that in my construction the air passageway 21 is larger than the orifice 19 and this is so constructed in order to avoid any possibility of clogging the air passage.

The restriction 22 varies in size depending upon 15 the length of the said passageway and the size of the fittings. This restriction of course is smaller than the air passage and the passageway leading to the valve 26 and the valve seat 27.

It will be observed from the construction which 20 has thus far been described that in my improved generator construction the valve 26 and the valve seat 27 are both outside of the region of the sub-fire, which plays wholly on the generator tube 18. Therefore in this improved construction the valve 25 is much cooler and is heated only by conduction and radiated heat and the valve should last indefinitely. When the valve forms a part of the generator as in prior structures it soon deteriorates and soon is clogged with carbon and therefore the operation of the burner is wholly unsatisfactory if not absolutely stopped.

It is rather difficult to obtain a packing material 30 that will stand the heat to which it is subjected and by reason of this fact I have inserted a tube 31' between the valve 26 and the packing gland 67. This places the packing gland near the front of the stove which is removed from the heat of the sub-fire as well as the heat of the burner so that the valve stem may be freely turned at all times.

40 It will also be noted that this improved generator burner is so made that the condensed gasoline can not drain into the sub-fire portion of the burner as the bottom of the mixing tube 2 is inclined and drains into the pocket 49 and immediately passes to the said drain tank 51. Therefore it is impossible for any condensed gasoline whatever to reach the burner. It would be most impractical to make a burner to be operated by my improved method of priming the generator if the condensed gasoline could reach the burner and thus drip from the burner. Such operation would be manifestly dangerous.

45 I find that if the burner should be made so that the condensed gasoline could drain into what I call the burner head it would be evaporated more rapidly and the vapor would not be sufficiently mixed with air and a yellow flame would occur at the burner slots above the condensed gasoline. The length of time it would take to completely 55 evaporate the condensed gasoline in the above construction, of course, depends upon the design of the burner and also upon how much gasoline had been condensed and had reached the burner.

60 In the instance of the several attempts heretofore mentioned in priming the burner it would naturally take a fairly large receptacle to hold the condensed gasoline. In my construction where the gasoline is at once drained away, failure to 65 properly prime the burner can not cause any trouble to a person failing to properly prime the generator, and he can immediately proceed to try again. Also, if for some reason the generator should not be completely closed and the gasoline 70 should leak to the burner, with my construction

it would first flow into the pocket 49 and be at once drained away to the drain tank 51.

Having explained the operation of the burner 1, and that the mixing tube 2 has communication 60 and 61 with the burners 12 and 13, I wish now to state that these burners are not provided with any generators whatever since the generator 18 provides sufficient vapor for the burner 1 and the burners 12 and 13 if they are to be operated.

75 When it is desired to operate either the burner 10 12 or 13 it is first necessary that the burner 1 be operated. The gasoline vapor in the mixing tube 2 is conveyed as stated to the tubes 60 and 61, and this gasoline vapor is controlled by a handle 68 that carries at its inner end a valve 69 that 15 controls the flow of the vapor from the cross tube 62 to the tube 60 that feeds it to the burner 12. This is a well known valve and its operation will be understood without further explanation.

A similar handle 70 has at its inner end a valve 20 similar to the valve 69 that controls the flow of vapor from the cross tube 62 to the burner 13. Hence the operation of these burners can be readily controlled by these valves and since these burners will not be put into operation until the 25 burner 1 is in full operation there will be no appreciable condensation of the vapor and hence there will be no gasoline in these burners to be taken care of and hence they are not connected with the drain chamber 51.

30

Top burner and connection with oven burner

The burner 1', its generator, its valve and its mixing tube are all constructed substantially as described in connection with the burner 1. However the burner 1' has a special construction differing from the burner 1. In describing this burner attention is particularly directed to Figures 9, 12 and 13. In the first instance I will explain that the mixing tube 2 of this burner 1' 40 has the extension 4' and projecting from this extension is a short tubular section 71 that communicates with the burner and controls the flow of gasoline vapor from the extension 4' to this burner. The burner now being described which is 45 shown in Figure 12 has a wall portion 72 provided with an opening 73 that is in communication with the tubular extension 71 of the said mixing tube. This opening 73 establishes communication between the tubular section 71 and 50 the burner openings 81. Also this tubular extension 71 has an opening 74 which communicates with a passageway 75 and the passageway 75 establishes communication between the tubular section 71 and the sub-fire burner 36, which sub- 55 fire burner is constructed exactly as the sub-fire burner of burner 1. Hence the sub-fire is always provided with vapor that plays on the generator 18 for heating it and generating vapor from the gasoline therein. The communication 75 only 60 communicates with the sub-fire and not with the slotted burner portions of the burner 1'. The opening 73 is controlled by a valve 76 that has a handle 77 connected with it so that by turning 65 this handle the valve can be opened and closed as may be required. This tubular connection 71 is provided with another opening 78 and this opening is controlled by a valve 79 which is similar to the valve 76 and it carries a handle 80 for operating the valve and thus controlling the passage 78.

The burner 1' also has a pocket 49 and with this pocket 49 the tube 52 is connected so that any condensed gasoline is collected in this pocket and 75

drained to the drain tank 51. When the valve 19 is closed the gasoline vapor can not flow through the pipe 64 to the oven burner 14 and as this valve is opened then the vapor will flow to the oven burner 14. Hence the flow and the amount of flow of vapor and hence the intensity of the fire produced by the oven burner 14 is controlled through the handle 80.

This burner 1' is primed in the manner explained in connection with the burner 1. Therefore the burner 1' being in full operation and it should be desired to operate the oven burner 14, it is only necessary to open the valve 19 when vapor will flow through the passageway 18 to the tubular connection 64 and then to the burner 14. Should it be desired not to operate the burner 1' this can be done by simply closing the valve 16. When this valve 16 is closed then the vapor flows through the passageway 14 to the sub-fire burner 36 so that vapor continues to be produced and fed to the mixing tubes 2, 4', tubular section 11 to the oven burner. By this arrangement of valves 16 and 19 either the burner 1' can be operated independently of the oven burner or the oven burner 14 can be operated independently of the burner 1' or both burners can be cut off and only the sub-fire burner for heating the generator will be operating. It is understood of course that the supply of vapor generated in the generator is controlled by the valve 32.

I am aware that it is not new to provide a connection between a top burner of a range and an oven burner and control this by means of valves. However it is believed to be new to have a sub-fire supplied with vapor independently of either the top burner or the oven burner and to control either one or both burners without affecting the operation of the sub-fire burner since the sub-fire communication is independent of the communication with either the oven burner or the top burner 1'.

By reference to Figure 13 it is shown that the communication 14 is with a chamber 15 that is separate from the burner openings thereabove and that the chamber 15 supplies vapor only to the sub-fire burner 36.

Construction of the burners

The burners 1, 1', 1² and 1³ have their upper portions comprised of six projecting slotted members 81 which have their inner ends separated as shown at 82 (Fig. 3) thereby forming in the upper part of the burners a substantially rectangular opening which extends downward in the burners substantially to their lower ends as shown in sectional view Figure 6, and below these slotted members or extensions is a passageway or chamber 83 which communicates so that the slotted extensions communicate one with the other and this chamber 83 communicates with the mixing tube 2 through the passageway 3. The burner 1 is provided with the sub-fire burner 36 which extends crosswise the said burner and this burner is located at one side of the opening 82 and as shown in Figure 6 the sub-fire burner has its upper portion 84 inclined thereby forming an inclined bottom for about half of the width of the opening 65. The inner vertical side of the sub-fire burner 36 is curved inwardly substantially as is indicated at 85 and the generator 18 is spaced from this curved portion of the sub-fire burner as illustrated in Figure 6. Each of the slotted extensions 81 are also separated as shown at 86 thereby forming right angle passageways across the burner.

These burners therefore produce a burner con-

sisting of six angular separated slotted extensions on their upper side and their inner ends separated by an opening 65 the bottom of the opening closed at one side by the sub-fire burner leaving the other side 87 open throughout the burner for the upward passage of air to assist in the combustion of the gas of the burner. The burner 1' differs from the burner 1 in that it has formed therein a vapor communication with the tubular member 11 of the mixing tube 2, the said communication being located on the outer side of the burner, and it also has formed in the front side under one of the slotted extensions 81 a passageway 89 that leads to the valve 16 that is operatively connected with the handle 11 for controlling the amount of vapor which passes to the passageway 89 between the slotted burner extensions 81.

Each of the burners 1² and 1³ has the slotted extensions 81 forming burners consisting of six 20 of said extensions.

From the foregoing description it will be seen that I have disclosed a method of generating gas from gasoline which involves supporting the raw gasoline so that the heavy particles are held in 25 solution within the generator whereby there is no substantial accumulation of carbon to interfere with the mechanism for controlling the flow of the vapor to the burner.

My improved burner and new method of vaporizing gasoline to substantially avoid the formation of carbon and its interference with the mechanism of the generator have been the result of work covering a considerable period of time. Based on a series of tests of this improved method 35 of vaporizing gasoline I find in carrying out this new method that gasoline is supported in the generator tube as illustrated in Figure 7 with its maintained level about at the point *a* illustrated in said figure. The lighter particles are vaporized and the vapor fills the space *b* and the heaviest particles are substantially at the surface of the gasoline and the heaviest particles are substantially mixed with the gasoline at the time they are vaporized and by reason of this operation carbon is substantially not accumulated within the generator tube 18. As I have previously stated, the lighter particles do not require much heat to vaporize while the heaviest require substantially a "cracking" of the gasoline 50 in order that they may be vaporized. Hence the heaviest particles are substantially mixed with the gasoline substantially at the point *a* at the time they are vaporized. My tests have led me to believe that the above is substantially the result 55 of my method here disclosed. Certain it is that the operation of this improved generator has convinced me that there is little or no accumulation of carbon, and that carbon is the result of the vaporization of the heaviest particles of 60 the gasoline.

In carrying out these tests I have operated my generators continuously day and night over a period of 2000 to 4000 hours, which is equivalent to a two to four year period of time that the 65 generator would be used in domestic cooking operations and without any interference whatever from the accumulation of carbon. Heretofore in the usual type of generators, as stated herein, carbon is formed quite rapidly and substantially 70 stops the operation of the burner in about 75 to 250 hours.

It will also be observed that I have utilized a method which prevents the raw gasoline which contains the heavy particles from coming in con- 75

tact with any of the mechanism that controls the flow of the gasoline to the burner, except when priming, when the raw gasoline serves to clean and flush the valve mechanism.

5 It will also be observed that I have discovered a new method of initially priming the burner by a blue flame and preventing the accumulation of condensed gasoline vapor by causing it to escape, thereby preventing what otherwise would 10 be a yellow flame in the initial starting of the burner.

10 I therefore will claim the above several methods in addition to the mechanisms for carrying out these several methods of generating and handling gasoline and vapor generated from the gasoline.

15 I have described in considerable detail the improvements but I wish it understood that I do not limit myself beyond a fair interpretation of 20 the appended claims.

Having thus described my invention what I claim and desire to secure by Letters Patent is:

1. The combination with a gasoline burner of means for producing an initial heating blue flame 25 comprising a burner housing having depending therefrom a sub-fire housing, a generator tube located under the burner and adjacent the sub-fire housing to be heated thereby, a pressure gasoline supply connected with the inlet end of the 30 generator, a valve mechanism connected with the outlet end of the generator, an air pressure tube having its inlet connected with said supply above the normal level of the gasoline in said supply, its outlet having communication with the said 35 valve mechanism, a manifold communicating with the said burner and the said sub-fire housing, the inlet end of the manifold in communication with the outlet end of the valve mechanism, whereby a blue initial heating flame for 40 the generator is produced.

2. An improved gasoline stove comprising a main burner, a sub-fire burner adjacent the main burner, a manifold in communication with said main burner and also with said sub-fire burner, a 45 generator tube adjacent said sub-fire burner and heated thereby, said generator tube having a fuel outlet in communication with said manifold, a gasoline supply for said generator tube, a valve controlling the fuel from said generator 50 tube to the manifold, and an air pressure supply communicating directly with said fuel supply from the generator tube, both said fuel and air supply jointly fed to said manifold, whereby an initial cold mixture of fuel and air is fed to 55 the manifold and thence to the main burners for producing an initial blue flame, for the purpose set forth.

3. An improved gasoline stove comprising a main burner, a sub-fire burner, a manifold having 60 communication with said burners, a generator tube adjacent the said sub-fire burner and heated thereby, means for producing an immediate blue flame from a cold mixture of fuel and air for preheating purposes, said means consisting of said generator tube, said generator tube having an outlet in communication with the manifold, a valve mechanism controlling said generator 65 outlet, said valve mechanism located out of direct contact with the said sub-fire burner, whereby accumulated carbon is prevented.

4. An improved gasoline stove comprising a main burner, a sub-fire burner, a manifold communicating with said burners, means for producing an immediate blue flame from a cold mixture of fuel and air for initially operating pur-

poses said means comprising a generator tube located adjacent said sub-fire burner and heated thereby and having a fuel outlet, a valve mechanism for controlling the fuel from said generator tube to said manifold, said valve mechanism located apart from and out of direct contact with the heat of said sub-fire burner, whereby accumulated carbon is prevented.

5. An improved gasoline stove comprising a main burner having a vertically arranged air passage 10 communicating above and below said burner, a sub-fire burner located below said passage-way and in communication with said main burner, a generator tube located adjacent to the sub-fire burner and heated thereby, a manifold 15 having communication with said burners, said generator tube having a combined air pressure and fuel outlet in communication with the manifold, a valve mechanism for controlling said air and fuel under pressure directly and jointly 20 from the said generator tube outlet, the parts operating to produce an initial blue flame for the main burner and lighting the sub-fire through the said passageway, the parts operating for the purpose set forth.

25 6. An improved gasoline stove comprising a main burner, a sub-fire burner communicating with and located adjacent the said main burner, a generator tube adjacent the said sub-fire burner and heated thereby, a manifold having a 30 fuel outlet communicating with said main burner, the generator tube having a fuel outlet communicating with said manifold, a pressure air supply communicating directly with said generator fuel outlet, a valve controlling said generator outlet whereby said main burner and said sub-fire burner both receive an initial cold mixture of fuel and air and whereby when said cold mixture of one of the burners is lighted the other burner is lighted thereby.

35 7. An improved gasoline stove comprising a main burner, a sub-fire burner communicating with said main burner, a manifold communicating with said burners, a generator tube adjacent said sub-fire burner and heated thereby, said generator tube having an outlet communicating with said manifold, a gasoline supply for said generator tube, a valve controlling said generator fuel outlet, a pressure air supply fed to the fuel outlet of the generator tube at a point in advance 45 of the fuel outlet thereby directly mixing said air with the said fuel, whereby an initial cold mixture is supplied to the manifold and there-through to the said burners for initially lighting and heating the said burners.

40 8. An improved gasoline stove comprising a main burner, a sub-fire burner communicating therewith, a generator tube adjacent said sub-fire burner and heated thereby, a gasoline supply for said generator tube, said generator tube 45 having a fuel outlet and an air pressure supply in communication with the said fuel outlet, a valve mechanism controlling said fuel and air pressure from the said generator outlet, a manifold adapted to receive said mixture of fuel and air from the generator outlet and said manifold also communicating with the main burner and said sub-fire burner whereby a cold mixture as it issues from said burner produces an initial blue flame, for the purpose set forth.

45 9. An improved gasoline stove comprising a main burner, a sub-fire burner communicating with the said main burner, a generator tube adjacent said sub-fire burner and heated thereby, said generator tube having a fuel outlet, an air

pressure supply directly communicating with said outlet end of the generator tube for causing a mixture of air and fuel in advance of said generator outlet, a gasoline supply for the generator 5 and a dual valve controlling mechanism for the outlet end of the generator, said dual valve controlling the flow of said air and gasoline therefrom, a manifold receiving said mixture in a cold condition and conveying it through the manifold 10 to the said burners, whereby said mixture as it flows from said main and sub-fire burners may be lighted in its cold condition for initial operation of said burners.

10. An improved gasoline stove comprising a 15 main burner, a sub-fire burner communicating with said main burner, a generator tube adjacent said sub-fire burner and heated thereby, a gasoline supply for said generator, the generator having a fuel outlet, an air pressure inlet tube 20 in communication with the outlet end of the generator tube whereby there is produced a cold mixture composed of air and fuel in advance of its final outlet, said generator provided with a valve adapted to control the flow of said fuel and 25 air therefrom, a manifold having an inlet end located to receive said cold mixture of air and fuel and said inlet end having an opening to receive a further air supply for said mixture, said mixture conveyed through the manifold to 30 said burners, whereby said cold mixture as it flows from the burners may be lighted for initial and temporary operation thereof, the parts operating as described.

11. An improved gasoline burner having 35 means producing a cold mixture of fuel and air under pressure to produce an initial blue flame including a main burner, a sub-fire burner having communication with the main burner, an inclined generator tube located between said 40 burners and having an outlet at its upper end, and also located adjacent the sub-fire to be heated thereby, a manifold having its inlet adjacent said generator outlet to receive fuel therefrom, said manifold also communicating with 45 said burners, a dual valve construction in the outlet end of the generator, an air pressure supply communicating with the outlet end of said generator tube, said dual valve controlling the flow of air thereto and the passage of fuel and 50 air therefrom to produce a cold mixture, said cold mixture flowing through the manifold to said burners, whereby a blue flame from said cold mixture can be ignited for producing a temporary heating flame, the parts combined for 55 the purpose set forth.

12. An improved gasoline stove comprising a main burner and a sub-fire burner having communication with the main burner, a generator tube located adjacent the sub-fire burner and

directly heated thereby, the generator tube having a fuel outlet located at one end thereof and extending at an angle to the said generator tube, a valve for controlling the fuel outlet located also at an angle to the said generator tube thereby placing the valve out of direct contact with the heat of the sub-fire burner, a manifold communicating with said generator fuel outlet and also with said burners, whereby the valve mechanism is located out of direct contact with the 10 heat of the burners and preventing an accumulation of carbon. 5

13. An improved gasoline stove comprising a main burner, a generator tube under said main burner having an outlet, said main burner having a hollow downwardly projecting portion located at one side of the said generator tube the lower end of said hollow projection provided with burner openings opposite said generator tube thereby constituting a sub-fire burner, a manifold having its inlet end receiving gasoline from 15 said generator outlet, said manifold also communicating with the main burner and through said downwardly projecting hollow member with said sub-fire burner, the parts adapted to operate 20 as set forth. 25

14. An improved gasoline burner supplying a temporary cold mixture of gasoline mist and air for producing an initial heating flame, comprising a main burner, a sub-fire burner thereunder 30 and communicating with the main burner, a generator tube located under said main burner and adjacent the sub-fire and heated thereby, a manifold receiving fuel from said generator tube and in communication with said burners, a 35 valve controlling said generator fuel to said manifold, whereby a cold mist composed of a mixture of gasoline and air is fed to the said manifold and through it to said burners for furnishing an initial blue flame for heating the said 40 generator tube, the parts arranged as described.

15. A construction for producing an initial blue flame from a cold mixture of fuel mist and air under pressure, comprising a main burner, a sub-fire burner under the main burner and in 45 communication therewith, a generator tube under the main burner and located adjacent the said sub-fire burner and heated thereby, said generator tube having a fuel outlet and also an inlet for the air pressure, means for supplying 50 said air pressure to the said generator tube outlet, a valve controlling the said generator outlet thereby producing a mixture of mist and air, a manifold receiving the said mixture of mist and air, the manifold having communication with 55 the said burners, whereby a temporary initial blue flame is produced for initially heating said burners.

I. VERNON BRUMBAUGH.
